UNITED STATES PATENT OFFICE

FRANK W. TICKNER, OF SHARON, AND JAMES THOMAS, OF SHARPSVILLE, PENNSYLVANIA, ASSIGNORS TO SHENANGO-PENN MOLD COMPANY, OF SHARPSVILLE, PENNSYLVANIA, A CORPORATION OF PENNSYLVANIA

MOLD PATTERN

Application filed February 4, 1929. Serial No. 337,248.

The present invention relates to mold patterns and more particularly to patterns for forming sand mold walls for use in casting metal. It relates still more particularly to an improved construction of such patterns, whereby to increase their strength and reduce the cost of manufacture.

Patterns for molding sand walls have heretofore been generally of two classes. Normally such patterns are made of wood, the molding surface being smoothed or finished to conform to the surface desired on the casting. In some instances patterns have been made of metal, comprising in themselves unitary castings.

Both of the classes of patterns above referred to have inherent disadvantages. Wooden patterns are comparatively fragile and their life is short. During the molding operation it is of course necessary to provide some means by which the pattern may be lifted to separate the pattern and mold. The usual practice when wooden patterns have been used is to screw metal eyes into the upper portions of the patterns to provide a connection for a crane hook or sling. Repeated lifting of the pattern, together with the jars, jolts and stresses to which it is normally subjected in use, not only cause a rapid deterioration of the pattern as a whole, but also tend to loosen the metal eyes so that the same often are stripped from the pattern during a lifting or carrying operation, further resulting in damage to the pattern. It is almost impossible to make a pattern which is formed substantially entirely of wood which is strong enough to withstand normal usage for any great period of time. Even though wooden patterns may retain their integrity they often become strained out of proper alignment and hence are of little value if accurate castings are to be made.

Metal patterns have two great disadvantages. The first of these is their excessive weight. Great weight is neither necessary nor desirable in a pattern as the pattern is merely used to serve as a retaining wall for sand packed thereagainst and no great stresses are imparted to it in the actual molding operation. Greater power is required to

lift heavy metal patterns than is required for lighter ones. The second disadvantage attendant upon metal patterns is their high cost due to the large mass of metal comprising them, and due to the necessity of casting each pattern in a specially prepared mold. Thus the wooden pattern is too light and fragile and easily destructible, whereas the metal pattern is too heavy, cumbersome and expensive.

We provide a pattern for molding sand for casting, comprising a composite wood and metal structure designed to obviate all of the various disadvantages above noted with respect to both the wooden and metal constructions heretofore known. We provide a pattern comprising a body of wood and metal braces extending lengthwise thereof for reinforcing and strengthening the pattern. We further provide a pattern comprising a wooden member forming a molding surface, and metal braces connected therewith for reinforcing and strengthening the pattern and projecting therefrom to provide means for lifting the pattern.

In the accompanying drawings we have shown certain present preferred embodiments of the invention, wherein,

Figure 1 is a horizontal cross section through a pattern,

Figure 2 is a partial elevation of the pattern shown in Figure 1,

Figure 3 is an elevation with a portion cut away of a pattern similar to that shown in Figures 1 and 2, but of a different shape,

Figure 4 is a vertical cross section through the pattern shown in Figure 3, and

Figure 5 is a top plan view of the pattern shown in Figures 3 and 4.

Referring more particularly to the drawings, reference numeral 2 designates generally a built up wooden structure forming the molding surface of the pattern. This structure may be of any desired shape, depending upon the shape of the mold in which the metal is to be poured. The pattern shown in Figures 1 and 2 is of square cross section with rounded corners and is adapted for the formation of a sand mold for casting ingot molds. This pattern has an outer

molding surface 3 and an inner molding surface 4 whereby it is adapted for the formation of both the core and cheek walls in the same packing or ramming operation. The 5 inner and outer walls are connected by braces 5, the structure being held together by any suitable fastening means such as nails, glue, or both.

The pattern shown in Figures 3, 4 and 5 10 is structurally similar to that of Figures 1 and 2, but is of round cross section. It has inner and outer molding surfaces 6 and 6^a, respectively, connected by braces 7.

The built up wooden structures are not of 15 themselves of sufficient strength to withstand the usage to which the patterns are put. In order to strengthen the patterns and to assist in maintaining their integrity and alinement, a metal construction is used, as will 20 now be described.

A metal plate 8 is provided at the top of 25 the wooden pattern member and another metal plate 9 is provided at its bottom. These plates preferably conform exactly to 30 the cross section of the wooden pattern member at its top and bottom, respectively. They are of sufficient thickness to assist in rigidly holding the pattern together, but are at the same time light enough not to unduly increase its weight.

Joining the plates 8 and 9 are metal rods 35 or bolts 10. Such rods or bolts are fastened to the bottom plate 9 in any suitable manner as by screw threads, as shown in Figures 3 and 4. They pass upwardly of the pattern between the inner and outer mold walls and at the top pass through holes appropriately provided in the plate 8. Nuts 11 are threaded over the upper extremities of the 40 members 10 and are tightened down against the plate 8. Thus the wooden pattern member is in effect compressed between the oppositely disposed metal plates 8 and 9, which are held together by a rigid metal structure 45 comprising the members 10 and the nuts 11. Some or all of the nuts are provided with eyes 12 for the reception of a crane hook or sling.

The members 10 are spaced and braced 50 with respect to the inner and outer mold walls by spacing members 13 disposed at intervals axially of the pattern. Such members not only prevent a possible looseness of the members 10 between the mold walls, but 55 assist in strengthening the wooden structure by bracing it at intervals against the metal rods. The wooden structure is thus braced both vertically from top to bottom and horizontally at intervals axially thereof.

In lifting, the stress is applied first to the 60 eyes 12, then to the rods 10, and is transmitted directly by such rods to the bottom plate 9. The wooden structure is subjected 65 to very little if any stress during the lifting

operation, as it is directly carried by the plate 9 through the agency of the rods 10.

The fact that the wooden structure is contained between the two oppositely disposed metal plates, and is somewhat compressed therebetween by reason of the nuts 11, prevents any appreciable looseness or tendency to disintegrate. The spacers 13 may extend completely around the pattern, thus even more rigidly holding it together.

Thus a pattern is provided combining lightness of weight, cheapness of manufacture, and strength. Although the embodiments shown in the drawings are particularly adapted for forming sand molds for casting ingot molds, it is to be understood that the invention is not limited to such type of pattern or to any similar type, but may be otherwise variously embodied within the scope of the following claims.

We claim:

1. A pattern for molding sand for casting, comprising a body of wood and metal braces extending lengthwise thereof for reinforcing and strengthening the pattern, the pattern being adapted to be moved intact from place to place.

2. A pattern for molding sand for casting, comprising a wooden member forming a molding surface, and metal braces connected therewith for reinforcing and strengthening the pattern and projecting therefrom to provide means for lifting the pattern.

3. A pattern for molding sand for casting, comprising a built-up wooden pattern member, and braces connected with the built-up member and extending from end to end thereof for maintaining the integrity of such member and reinforcing and strengthening the same, the pattern being adapted to be moved intact from place to place.

4. A pattern for molding sand for casting, comprising an elongated wooden pattern member, and brace rods extending longitudinally of the pattern member and having their ends shaped to provide means for lifting the pattern.

5. A pattern for molding sand for casting, comprising a wooden pattern member, a metal strengthening member on the bottom thereof, and metal members connected with the strengthening member and extending upwardly of the pattern to provide means for lifting the pattern.

6. A pattern for molding sand for casting, comprising a wooden pattern member, metal plates on the top and bottom thereof, and braces connecting the plates.

7. A pattern for molding sand for casting, comprising a hollow wooden pattern member having molding surfaces on both the inside and outside thereof, and metallic strengthening means connected with the pattern member and providing means for taking a lifting stress to lift the pattern.

8. A pattern for molding sand for casting, comprising a pattern member having inner and outer molding surfaces, and bracing members connected with the pattern member and extending therealong between said molding surfaces.

9. A pattern for molding sand for casting, comprising a pattern member having inner and outer molding surfaces, metal strengthening members at the top and bottom of the pattern member, and brace rods extending between the inner and outer molding surfaces and connecting the strengthening members.

10. A pattern for molding sand for casting, comprising a built-up wooden pattern member having inner and outer molding surfaces, and metal strengthening members between the inner and outer molding surfaces for maintaining the integrity of the pattern and reinforcing and strengthening the same.

11. A pattern for molding sand for casting, comprising an elongated pattern member, a plate at the bottom thereof, and rods connected with the plate and extending upwardly of the pattern member, the rods having at their upper ends means for attaching lifting means for lifting the pattern.

In testimony whereof we have hereunto set our hands.

FRANK W. TICKNER.
JAMES THOMAS.
